U.S. Cl. D9—267

FIG. 1

FIG. 2

FIG. 3

FIG. 4

FIG. 7

FIG. 5

FIG. 6

FIG. 1 is a top plan view of a lid for a packaging container or the like showing my new design;

FIG. 2 is a front elevational view;

FIG. 3 is a bottom plan view;

FIG. 4 is an enlarged scale fragmentary elevational view;

FIG. 5 is an enlarged scale cross-sectional view taken along line 5-5 of FIG. 4;

FIG. 6 is an enlarged scale cross-sectional view taken along line 6-6 of FIG. 4; and

FIG. 7 is an enlarged fragmentary cross sectional view taken along section line 7-7 of FIG. 1.

It is understood that the corrugated ornamentation shown fragmentarily about the flat periphery is continuous throughout such periphery in the path indicated.

I claim:

The ornamental design for a lid for a packaging container or the like, as shown and described.
